DESIGN FOR A SHAVING BOWL OR SIMILAR ARTICLE

Albert Mosheim, New York, N. Y.

Application April 13, 1936, Serial No. 62,094

Term of patent 3½ years

To all whom it may concern:

Be it known that I, Albert Mosheim, a citizen of the United States and a resident of the city of New York, county of New York, and State of New York, have invented a certain new, original, and ornamental Design for a Shaving Bowl or Similar Article, of which the following is a specification, reference being had to the accompanying drawing, forming part thereof.

Figure 1 is a plan view of a shaving bowl or similar article illustrating my design; and

I claim:

The ornamental design for a shaving bowl or similar article substantially as shown and described.

ALBERT MOSHEIM.
